UNITED STATES PATENT OFFICE.

LAWRENCE A. ABBOTT, OF CHICAGO, ILLINOIS.

AUTOMATIC CLOSING DEVICE FOR SLIDING DOORS.

1,169,755.

Specification of Letters Patent.

Patented Feb. 1, 1916.

Application filed August 19, 1912. Serial No. 715,760.

To all whom it may concern:

Be it known that I, LAWRENCE A. ABBOTT, a citizen of the United States, and a resident of the city of Chicago, in the county of Cook and State of Illinois, have invented certain new and useful Improvements in Automatic Closing Devices for Sliding Dcors; and I do hereby declare that the following is a full, clear, and exact description of the same, reference being had to the accompanying drawings, and to the numbers of reference marked thereon, which form a part of this specification.

This invention is adapted for use for insuring the closure of hatchway or elevator doors or sliding doors of any kind.

Although it is the usual requirement of the underwriters in the various cities, that hatchway doors should be fully closed before the elevator leaves the floor, to which the door opens, in practice, the operator, if he attempts to close the door at all, usually starts the closing movement at about the same time that he starts the cage or platform. In consequence, where such doors are closed manually, it frequently occurs that the door is not wholly closed, leaving the hatchway unguarded and inviting accident.

Although automatically closing devices have been introduced to some extent, such devices, as a rule, close the doors with considerable violence, usually the velocity of the door in closing, increasing as it approaches a fully closed position, so that should a person attempting to leave or enter the car be struck or caught between the door sections, he would be likely to be firmly held and almost certainly severely injured.

The object of this invention is to afford an automatic closing device for sliding doors so constructed and installed that the door starts automatically to close when released by the operator, the closing movement decreasing in velocity from near the end of the closing movement until the dcor or doors are brought to closed position, gently, though positively.

It is also an object of the invention to afford a construction in which the opening of the door stores sufficient energy to return the same to closed position when released.

It is a further object of the invention to afford a construction in which energy is stored in a spring during the opening of the door, said spring acting torsionally to im-

pel the doors to closed position when released and to produce quick, though gentle, closure.

The invention embraces many novel features and consists in the matters hereinafter described and more fully pointed out and defined in the appended claims.

In the drawings: Figure 1 is a fragmentary front elevation, showing two oppositely slideable doors equipped with automatic closing means embodying my invention. Fig. 2 is an enlarged fragmentary view showing one of the doors with the closing means therefor broken away. Fig. 3 is an enlarged section taken on line 3—3 of Fig. 2, with the door omitted. Fig. 4 is an enlarged section on line 4—4 of Fig. 2. Fig. 5 is an enlarged sectional detail of one of the outer or end bearings for the spiral shaft. Fig. 6 is an enlarged fragmentary sectional view of the center bearing for the actuating shaft.

As shown in the drawings: 1, indicates a wall having an opening therethrough, at which is slidably supported a door comprising sections 2 and 3, adapted to close said opening and operated to close automatically.

As shown, ways or guides for said door are secured horizontally on the wall above the same. For this purpose, if preferred, a flat plate or bar 4, may be rigidly secured to the wall by riveting or bolting, and secured thereto are upper and lower ways 5 and 6, which extend horizontally above and on each side the door at equal distances apart, and for a length sufficient to permit the required travel of the door sections to full opening. Said guide bars 5 and 6, are concaved in their adjacent edges, as shown in Fig. 3, and slidably engaged therebetween on anti-friction balls 7, are the sliding bars 8, one for each door, and the doors 2 and 3, are hung thereon to depend below the same by means of metallic angle straps 9, two of which are rigidly bolted to the top of each door section near the edges of thereof, as shown in Fig. 4, and extend upwardly transversely the bar 8, and are secured thereto by means of a bolt 10, passing through the extremity thereof and engage in the sliding bar.

Secured on the plate 4, above the way 5, and above the middle of each door, is a bracket 11, in which is journaled a shaft 12, having an integral peripheral collar near

each end thereof, which is grooved on the outer side to receive therein balls 13, which operate in a groove in the face of the bracket, as shown in Fig. 6, to afford a ball bearing for said shaft at each end.

Rigidly connected at each end of said shaft are oppositely directed right and left screw shafts 14 and 15, formed, as shown, as from a flat bar of steel twisted spirally for its entire length. Each of said screw shafts at its outer end is provided with an integral central projection 16, provided with a spacing collar 17, thereon and which projects through said collar and into a suitable bracket 18, secured on the back plate 4, and in which is a roller bearing 19, in which said projection is journaled. Said bracket beyond the roller bearing and in alignment with the projection, is provided with a seat 20, in which is contained a ball 21, which bears against a plate 22, and an adjusting screw 23, extends axially through the head of said bearing and carries a plate 24, which bears against said ball to take the thrust at all times of the screw shaft.

Secured on each of the sliding bars 8, above the middle of each door, is a bracket 25, having rollers 26 and 27, journaled therein, one above another, the axes of which are parallel and on opposite sides of the screw shaft, as shown in Fig. 3. As shown, said rollers are reduced slightly in circumference at the ends to afford a slightly convexed bearing face on the screw shaft. A strong spiral spring 28, is secured at one end on the collar 12, on the shaft 12, and is wound about said shaft 12, and at the other end engages in the back plate 4, as shown in Figs. 1 and 2.

The operation is as follows: The spring is set at neutral or to exert very slight torsional stress when the doors are closed. When either door is impelled to open position by sliding the same laterally, such lateral movement rotates the shaft by the engagement of the rollers on said spiral shafts 14 and 15, and both doors move outwardly and oppositely, and may be held in open position by any suitable means or manually. At the moment the door is released, however, from open position, the torsion of the spring 28, reverses the rotation of the shaft, whereby the doors are impelled inwardly toward closed position, the speed of such movement beginning to decrease when the doors are nearly closed, and decreasing until fully closed, owing to the decreasing torsional action of the spring.

Whichever door is actuated in opening, the ball roller bearings receive all the thrust thereof. The construction is such as to permit the doors to yield very readily in opening and in winding up the spring, which need not be of great strength owing to the fact that the shafts are journaled upon ball

and roller bearings, the doors supported upon ball bearings, and a roller bearing is afforded upon the screw shaft to afford the bearing for actuating the doors.

Of course, details of the construction may be varied, and I do not purpose limiting the patent issued on this application for patent otherwise than necessitated by the prior art.

I claim as my invention:

1. In a device of the class described a pair of oppositely disposed right and left handed thread worm shafts, an intermediate member rigidly connected to the adjacent ends of said worm shafts, bearings supporting said intermediate member and worm shafts, integral flanges on said intermediate member affording together with said bearing a ball race for a thrust bearing, and a spring wound about said intermediate member and attached thereto and to a fixed support to resist rotation of said intermediate member and worm shafts.

2. In a device of the class described a pair of right and left handed threaded worm shafts, an intermediate member rigidly connected to each, grooved flanges integrally formed on said intermediate member, grooved supporting brackets for said member and co-operating with said flanges to afford a thrust ball bearing therefor, a spring wound around said member and connected to one of said flanges and to a fixed support to resist rotation of said member, and roller ball-bearing mechanism engaging said worm shafts adapted to progress therewith along with rotation of said shafts.

3. In a device of the class described a plurality of worm shafts arranged in axial alignment, a spring controlled intermediate member rigidly connected to each of said shafts to resist movement thereof in a certain direction, door supporting brackets engaging around said worm shafts, and rollers journaled in said brackets adapted to contact opposite faces of said worm shafts to cause progression of said brackets longitudinally of said worm shafts with rotation of said shafts.

4. In a device of the class described grooved brackets rigidly secured upon a wall, a shaft journaled in said brackets having an integral peripheral grooved collar near each end thereof, ball bearings, said brackets and said collars arranged to afford a race for said ball bearings, a worm shaft rigidly connected at each end of said shaft in axial alignment therewith, an integral projection on the outer end of said worm shafts, a spacing member thereon, a pair of apertured brackets rigidly secured on said wall, rollers therein adapted to receive said projections journaled therebetween, adjustable ball bearing means mounted in said apertured brackets to take the thrust of said worm shafts, roller door supporting mem-

bers movably engaged with said worm shafts, and a spring wound around said first mentioned shaft having one end thereof secured in one of said grooved collars and the other end thereof rigidly fastened to the wall, said spring acting to automatically close the doors when the same have been opened.

In testimony whereof I have hereunto subscribed my name in the presence of two ^{to} subscribing witnesses.

LAWRENCE A. ABBOTT.
